WILLIAM TWEEDDALE AND JONATHAN MOORE, OF BROOKLYN, NEW YORK,
ASSIGNORS TO THE NORTH AMERICAN IRON-WORKS, OF SAME PLACE.

DESIGN FOR A VASE.

Specification forming part of Design No. 7,512, dated June 30, 1874; application filed May 1, 1874.
[Term of Patent 7 years.]

CASE A.

To all whom it may concern:

Be it known that we, WILLIAM TWEEDDALE and JONATHAN MOORE, of Brooklyn, in the county of Kings and State of New York, have invented a new and original Design for a Vase, of which the following is a specification:

Our design is fully represented in the accompanying illustration, to which reference is made.

The said design consists, first, of the figured band A on the border of the outside of the vase at the upper edge, composed of figures, substantially as represented in the illustration; second, of the side ornaments, consisting of the parallel plain, oval, or elliptical bands B, the wreath C between the bands, and the top and bottom ornamental figures D E; third, of the foliate figures F on the sides and on each side of the elliptical middle side figure; fourth, of the foliate lower side and bottom figures G H; fifth, of the scroll, flute, and point-shaped ornamentation G' of the handles and the dragon-head H' and wing I, surmounting the handles; sixth, of the ornamental form of the standard J and the figures K on the base of said standard; seventh, of the ornamental figures L, together with the oval center-piece M on the panels of the pedestal or base; eighth, of the ornamental configuration of the pillars N at the corners of the base.

We claim as our invention—

1. A design for a vase, in which the border A is ornamented, as shown and set forth.

2. A design for a vase, in which the sides are ornamented with the plain bands B, wreaths C, and figures D and E, as shown and set forth.

3. A design for a vase, in which the sides are ornamented by the ornamental figures F, as shown and set forth.

4. A design for a vase, in which the lower sides and bottom are ornamented by the figures G and H, as shown and set forth.

5. A design for a vase, in which the handles are ornamented by the figures G' H' I, as shown and set forth.

6. A design for a vase, consisting of the ornamental border A, side figures B, C, D, and E, bottom figures G H, and the handle ornaments G' H' I, as shown and set forth.

7. A design for a vase, consisting of the ornamental configuration of the standard J and the figures K on the base of said standard, as shown and set forth.

8. A design for a vase, consisting of the ornamental figures L and the oval center-piece M on the panel of the pedestal, as shown and set forth.

9. A design for a vase, consisting of the ornamental configuration of the pillars N of the corners of the base, substantially as specified.
